FLASH DRYING CONTROL

Alfred R. Smith, Forest Hills, Long Island, N. Y.,
assignor to Combustion Engineering Company,
Inc., New York, N. Y.

Application January 23, 1936, Serial No. 60,456

7 Claims. (Cl. 34—34)

This invention relates to improvements in apparatus for drying materials by the so-called "flash-drying" method. In this method, the wet material in comminuted form is intimately mixed with a hot gaseous drying medium and is maintained in suspension until it is dried to the desired point. The process may be used not only when materials are merely dried without changing any of their other characteristics, but also where one or another of such other characteristics is to be changed, as for example, in the reduction or removal of water of crystallization, in distillation or in sublimation.

It is important in the flash drying process, as distinguished from the usual drying process such as by means of a rotary drier, that all the material particles be maintained in suspension and agitation during the process, thereby subjecting them to continuous contact with the drying medium, which assures to all particles a substantially equal and uniform rate of drying. The accumulation of material which may occur within the usual forms of driers is thereby avoided and therewith the danger of overheating particles that linger within the drier longer than the time required for their drying.

It is also important for rapid or flash drying to have the particle size small for various reasons, one being that a relatively large surface of material is thus exposed to the drying medium. The finer the particle size the greater will be the ratio of particle surface area to weight of particle and hence weight of moisture. Another reason for having small particle size is to assure a substantially uniform temperature throughout the particle during drying, for should the rate of surface drying be too fast this will tend to overheat and scorch the surface, and this danger is greater if the particles are large.

In accordance with the present invention the temperature of the material being dried by such a flash method is controlled whereby hotter drying media can be more safely used than heretofore and whereby the drying can be done more quickly and more cheaply and the dried material is of superior quality.

The improvement is particularly applicable to materials which must not during the drying be raised beyond certain temperatures in order to preserve vitamins therein or to otherwise avoid impairing the qualities of the materials, e. g. by oxidation or by the destruction of organic life therein, or to avoid releasing obnoxious odors therefrom. This is due to the fact that definite

control is present of the temperature of all the particles.

An object of the invention then is to provide in a drying process employing a high temperature drying medium, means for maintaining a substantially uniform temperature of all particles of the material being dried and to maintain said particles' temperature at a predetermined value throughout the drying period.

How the foregoing together with such other objects and advantages as may hereinafter appear, or are incident to my invention, are realized, is illustrated in preferred form in the accompanying drawings, wherein:

Fig. 1 is a diagrammatic illustration of a flash drying system embodying the invention;

Figures 2 and 3 show modifications of the arrangement shown in Fig. 1;

Fig. 4 is a partial reproduction of a conventional psychrometric chart.

Fig. 5 shows one control means;

Fig. 6 shows another control means.

The wet material to be dried may be admitted through conduit 10 into a feeder 11 where it is preferably mixed with a predetermined amount of dried material from the surge bin 12 and thence delivered to the drier 13. If a pressure difference exists between the mixer and drier a seal or pressure lock 14 may be provided. On arriving in drier 13 the material is caught by the current of drying medium entering through conduit 15 and maintained in flotation through the drier and thence delivered by fan 16 to separator 17 via conduit 18, in which separator the material and drying medium are separated. The material is delivered to the surge bin 12 for use in mixing it with the raw material in mixer 11, or for delivery of the finished product through spout 20. A seal 21 may be provided in the feeder line from the separator to the bin in case a difference of pressure exists between the two.

On leaving the separator, the separated drying medium is in controlled part conducted to the drier 13 through conduit 19, 15 and in controlled part conducted to condenser 22. That part of the drying medium led to condenser 22 has substantially all of its moisture removed by condensation and the remaining gas is deodorized as indicated at 23, by suitable means such as by dilution, by adsorption by activated materials such as carbon, bone black or by other means. The condensate may be disposed to waste or to the recovery of certain ingredients if desired. Before entering the drier 13, the recirculated drying medium merges with controlled amounts of cold gases 55

through inlet 24 and/or hot gases from furnace 25, through conduit 26. The drier 13 is of such construction as to maintain the material in suspension and agitation throughout the drying process and may be of the spray type, an impact type of pulverizer mill or an agitator as shown in a copending patent application Ser. No. 720,417, now Patent No. 2,033,757, dated March 10, 1936.

The theory underlying the invention is that a moisture carrying particle which is to be dried resembles a wet-bulb thermometer and therefore that when dried in a chamber by hot gas or heated vapor introduced thereto the temperature of the particle corresponds with the wet bulb temperature of the drying medium. These observations have led to the further discovery that by maintaining a constant wet-bulb temperature in a drying apparatus the heat of the drying medium may be utilized to absorb moisture from the particle while the latter is protected by maintaining it at a constant wet-bulb temperature.

It is known that when moisture in the form of a spray or associated with solid particles is introduced into a chamber containing air and superheated moisture the wet-bulb temperature of the air-vapor mixture remains constant. During the time that moisture is being introduced (up to the saturation point which is never reached in practical operation) the dry-bulb temperature is dropping. This drop in temperature represents sensible heat of the air-vapor mixture passing into latent heat of vaporization for the water being introduced. Since there is substantially no addition or withdrawal of heat in this process, the total heat remains substantially the same and the wet-bulb temperature remains substantially constant.

The wet-bulb temperature is a measure of the temperature of the liquid within a wick surrounding a thermometer some of which liquid is evaporating to the surrounding air-vapor mixture. Similarly a wet particle being dried within the drier is substantially at or near the wet-bulb temperature. If then the wet-bulb temperature of the drying medium is kept at a predetermined point, the material temperature will be kept at substantially the same temperature and the material will thereby be protected from over-heating. It is well to note that wet bulb temperatures may be measured at dry bulb temperatures well above the boiling point of the moisture being evaporated whereas relative humidity is non-existent at temperatures above the boiling point and consequently would not be indicated by a hygrometer or similar device.

One may use various drying media such as dry gas, a mixture of gas and water vapor or superheated steam or other vapor alone. When using a mixture of gas and water vapor, the psychrometric laws mentioned apply and the temperature of the material to be dried may be controlled by the wet-bulb temperature which is a measure of the temperature of the material. When using a superheated vapor alone, the temperature of the material to be dried may be controlled by the vapor temperature corresponding to the vapor pressure maintained during the drying period within the drier, this being substantially the final temperature of the material after being dried to the desired degree. Should for example atmospheric pressure prevail within the drier, the wet-bulb temperature of the vapor will be 212 deg. F. and as long as a residual of moisture is present in the material to be dried, its temperature will remain substantially at 212 deg.

F. In the use of either a gas and vapor mixture or superheated vapor for a drying medium, the wet-bulb temperature, which is one equivalent of the final dried materials temperature, serves according to the invention as a control means for protection against overdrying and possible injury to the material.

According to the invention, means responsive to the wet-bulb temperature of the drying circuit are provided for controlling the heat input to the drier. Such means may be placed in Fig. 1 at locations such as A, B or C for if substantially no further heat is added or abstracted beyond A in the direction of flow, the wet-bulb temperature will be substantially the same for the purpose of the control, en route to and at these various locations. The means may be such as shown in Fig. 5 in which gas is withdrawn from the circuit through a connection 30 at one of the mentioned locations, preferably passed through a filter 31 and then over an element enveloped in a wetted wick, the expansion and contraction of the element being responsive to variations in the wet-bulb temperature and actuating damper control means. For example, a bellows 32, enveloped by wick 33 which dips into a liquid in a reservoir 34 and maintained wet thereby, is provided with stem 35, which with rise and fall of the bellows, may contact one or the other of the terminals 36, 37 of a switch controlling a reversible motor 38. Motor 38 may be connected by any suitable means to act to open or close a damper or dampers in the conduits of the drying circuit.

Referring to Figure 1, the numerals 40, 41, 42 represent control valves or dampers; damper 40 being in the hot gas supply line 26 from the source of heat 25; 41 in the air supply line 24, and 42 in the return line 19. Damper 40 may be alternatively replaced by dampers 40a, 40b in the air and fuel lines to furnace 25. The dampers 40, 41, 42 are arranged to be operated by the motor, or motors, 38 in response to wet-bulb temperature at B, or other convenient point, as follows:

Change in wet-bulb temperature	Movement of dampers		
	40	41	42
Rising-----	Closing-----	Opening-----	Closing-----
Falling-----	Opening-----	Closing-----	Opening-----

A means for controlling damper movements as tabulated above is shown in Fig. 1 where 32 represents the wet-bulb device of Fig. 5 and dampers 40, 41 and 42 are actuated by a common connecting rod 39 operated by motor 38.

Fig. 4 is a partial reproduction of a conventional psychrometric chart on which the line a—e represents a chosen limiting constant wet bulb or materials temperature. It will be understood that when drying or treating various materials the wet bulb temperature selected for control will be that best suited to the particular material and the extent of drying or other treatment to which it is to be subjected. The fresh hot gas from furnace 25 having been raised from room temperature t_1 to temperature t_2 is discharged through conduit 26 and commingles with the moist recirculated drying medium returning through conduit 19 at a temperature of about t_2 and a moisture content m_2 . While commingling there is an interchange of moisture and heat between the recirculated mixture and hot gas which

stabilizes in a resulting mixture at a temperature t_3 and moisture content m_3 as indicated at a in Fig. 4.

When mixed with the material which is to be dried part of the sensible heat of the drying medium passes into latent heat of vaporization for the water introduced with the material and the dry bulb temperature of the drying medium drops. The portion of the drop in dry bulb temperature used for sensible heat to bring the introduced moisture and material to the wet bulb temperature is but a small proportion of the total drop in dry bulb temperature and takes place in a small part of the time for drying the materials so that during the drying process the total moisture present is substantially constant at the optimum wet-bulb temperature.

During the drying period the drying medium entering at dry-bulb temperature t_3 with a moisture content m_3 , as represented at point a on Fig. 4, absorbs moisture from the material as its dry bulb temperature falls from t_3 to t_2 while its wet bulb temperature is maintained constant, or substantially so as mentioned above, along the line $a-e$.

The return of part of the drying medium through conduit 19 increases the amount of moisture introduced into the drier and if the amount of recirculated medium commingled with the fresh hot gas is excessive as compared with the amount of fresh hot gas with which it is commingled the wet bulb temperature of the drying medium on entering the drier would be above the optimum value a , as indicated for example at b in Fig. 4.

If during the drying process the temperature of the drying medium on entering the drier exceeded the optimum temperature t_3 for the moisture content m_3 by entering the drier at a temperature t_4 the wet bulb temperature of the drying medium would be higher as indicated at point d and this departure from desired conditions also would be detected by the wet-bulb apparatus 32.

However, as the wet-bulb temperature rises to b or d the control mechanism acts to close dampers 40 and 42 and to open damper 41. Closing of damper 42 reduces the amount of recirculated medium and lowers the amount of moisture entering the drier. Opening of damper 41 increases the quantity of cool air and thus reduces the temperature of the drying medium, the amount of which is also reduced by closing damper 40. These regulating movements of the dampers 40, 41, 42 act to restore the wet-bulb temperature to the selected value or along line $a-e$ and tend to maintain a substantially constant wet-bulb temperature in the drier so that the material being dried is likewise maintained at a substantially constant temperature.

It is known that heretofore attempts have been made to maintain determined input and outlet temperatures such as t_3 and t_2 by measuring the dry-bulb temperatures at inlet and outlet of the drier and then regulating the temperature and amount of drying medium admitted to the drier. However, a dry-bulb temperature t_3 might prevail and be so indicated while the moisture content of the drying medium might be anywhere along the line t_3 (as too high at b or too low at c) without any indication being given of these conditions since the dry-bulb device is incapable of detecting the variations in moisture content of the drying medium. Furthermore, although an outlet dry bulb temperature t_2 for the

drying medium might be indicated both the moisture content and condition of the treated material might vary widely. For example, at an outlet temperature of t_2 , the material might retain a large part of its moisture or conversely might be overheated while the drying medium might give the same dry-bulb reading in either case. In short, the dry-bulb temperatures alone do not afford accurate indication of the condition of the material to determine whether it has been overheated.

In the arrangement of Figure 2, the materials temperature is maintained by connecting the wet-bulb apparatus 32 to control the amount of recirculated drying medium by regulating damper 42 and in Figure 3 the temperature of the flash drying medium is controlled by dampers 40 and 41 or dampers 40a, 40b. In these arrangements, one or two respectively of the variables affecting the wet-bulb temperature of the drying medium are automatically controlled by the wet-bulb device rather than all as in Fig. 1.

The total heat required from the drying medium for eliminating a fixed amount of moisture from the material is a definite quantity. If the quantity of the drying medium is more than required, the resulting dry-bulb temperature leaving the drier may be relatively high and heat will be wasted. If the amount of heated drying medium were excessive as compared with the amount of materials to be dried, the particles might have all their moisture absorbed by the drying medium when the dry bulb temperature of the latter had fallen to point g for example. Thereafter the contact of the drying medium with the material would raise the temperature of the latter as heat passed from the drying medium to the material with consequent danger of drying the latter beyond the point desired or even scorching the material. When the quantity is less than required, the resulting dry bulb temperature may be relatively low and the rate of drying, which falls off with drop in the temperature of the drying medium, may become too small and drying may not be carried far enough to dry the material to the extent desired. In accordance with the invention, I may control the quantity of drying medium by the dry-bulb temperatures in the circuit before and after the drier, in addition to the above mentioned controls, thereby effecting an economical use of the heat supplied as well as a substantial control of the extent of drying.

In the arrangement of Fig. 2, a suitable thermostatic device 44 at the inlet of drier 13 is connected to control a motor 45 operating air damper 41 and damper 40 which regulates the amount of hot gas, or in place of these dampers the air and fuel dampers 40a, 40b, thereby maintaining a substantially constant inlet temperature t_3 . A thermostat 46 at the outlet of the drier, or in conduit 19, controls a motor 47 operating a damper 48 regulating the amount of drying medium entering the drier thereby cooperating to maintain a substantially constant outlet temperature t_2 . Thermostat 46 might also control the speed of fan 16, through a rheostat 49 as indicated in Figure 6. In this arrangement the wet-bulb temperature apparatus 32 controls the damper 42 to regulate the amount of recirculated drying medium and hence cooperates with the thermostatic devices to regulate the moisture content of the drying medium admitted to the drier. The temperatures t_3 and t_2 are then maintained by the thermostats 44, 46.

46 as limits for the drying medium between which the drying process takes place along line 5
a—e for each unit quantity of drying medium. Assuming a uniform flow and moisture content 10
5 of the material to be dried through the drier, the control of temperatures t_2 and t_3 then proportions the quantity of drying medium so that each unit thereof will absorb a predetermined amount of moisture from a to e, which range 15
10 is preferably such that most economical operation of the process will result.

The novel features of this invention may be applied to driers which receive previously ground material and are constructed to maintain the 15 material in substantial flotation and agitation during the drying process, or to mills which serve as driers and which may receive coarse material and grind it while it is simultaneously being dried within the mill.

20 The return of vapor from the separator 17 to the drier for diluting hot gas results in an increase in efficiency and it is therefore desirable to recirculate a maximum of said gas. By the controls in accordance with this invention, such 25 maximum recirculation may be safely employed without the danger of overheating the material being dried.

What I claim is:

1. In flash drying apparatus of the type described in which finely comminuted moisture-carrying material is fed into a drying chamber and intimately commingled with and carried by a heated gaseous drying medium at above 212° F. that absorbs moisture from said material and 30 wherein the material and drying medium are withdrawn from the drying chamber and separated and at least a portion of the separated moisture retaining drying medium is mixed with a fresh supply of heated drying medium and returned to the drying chamber for drying wet incoming material; means for supplying a predetermined constant amount of freshly heated drying medium to said chamber; means for regulating the amount of returned moisture carrying 35 drying medium; and means for maintaining said material at a substantially constant temperature during the drying period consisting of means responsive to the wet bulb temperature of said drying medium for controlling said regulating 40 means to vary the amount of heat retaining moisture carrying drying medium returned to the drying chamber.

2. In flash drying apparatus of the type described in which finely comminuted moisture carrying material is fed into a drying chamber and intimately commingled with and carried by a heated gaseous drying medium at above 212° F. that absorbs moisture from said material and 45 wherein the material and drying medium are withdrawn from the drying chamber and separated and at least a portion of the separated moisture retaining drying medium is mixed with a fresh supply of heated drying medium and returned to the drying chamber for drying wet incoming material; means for returning a predetermined constant amount of moisture-carrying medium to said chamber; means for regulating the amount of freshly heated drying medium supplied to said chamber; and means for maintaining said material at a substantially constant temperature 50 during the drying period consisting of means responsive to the wet bulb temperature of said drying medium for controlling said regulating means to vary the amount of heat retaining moisture carrying drying medium returned to the drying 55 chamber.

heated drying medium supplied to the drying chamber.

3. In flash drying apparatus of the type described in which finely comminuted moisture-carrying material is fed into a drying chamber and intimately commingled with and carried by a heated gaseous drying medium at above 212° F. that absorbs moisture from said material and wherein the material and drying medium are withdrawn from the drying chamber and separated and at least a portion of the separated moisture retaining drying medium is mixed with a fresh supply of heated drying medium and cool gas and returned to the drying chamber for drying wet incoming material; means for returning a predetermined constant amount of moisture-carrying drying medium to said chamber; means for regulating the amount of freshly heated drying medium supplied to said chamber; means for regulating the amount of cool gas supplied to said chamber; and means for maintaining said material at a substantially constant temperature during the drying period consisting of means responsive to the wet bulb temperature of said drying medium for controlling said regulating means to vary the amounts of cool gas and freshly heated drying medium entering the drying chamber.

4. In flash drying apparatus of the type described in which finely comminuted moisture carrying material is fed into a drying chamber and intimately commingled with and carried by a heated gaseous drying medium at above 212° F. that absorbs moisture from said material and wherein the material and drying medium are withdrawn from the drying chamber and separated and at least a portion of the separated moisture retaining drying medium is mixed with a fresh supply of heated drying medium and returned to the drying chamber for drying wet incoming material; means for regulating the amount of separated drying medium returned to the drying chamber; means for maintaining said material at a substantially constant temperature during the drying period consisting of means responsive to the wet bulb temperature of said drying medium for controlling said regulating means to vary the amount of heat retaining moisture carrying drying medium returned to the drying chamber; and means responsive to the dry bulb temperature of the drying medium at the inlet of said chamber for regulating the amount of freshly heated drying medium supplied to said chamber.

5. In flash drying apparatus of the type described in which finely comminuted moisture carrying material is fed into a drying chamber and intimately commingled with and carried by a heated gaseous drying medium at above 212° F. that absorbs moisture from said material and wherein the material and drying medium are withdrawn from the drying chamber and separated and at least a portion of the separated moisture retaining drying medium is mixed with a fresh supply of heated drying medium and returned to the drying chamber for drying wet incoming material; means for regulating the amount of separated drying medium returned to the drying chamber; means for maintaining said material at a substantially constant temperature during the drying period consisting of means responsive to the wet bulb temperature of said drying medium for controlling said regulating means to vary the amount of heat retaining moisture carrying drying medium returned to the drying 70 chamber.

chamber; and means responsive to the dry bulb temperature of the drying medium after a substantial amount of drying has occurred for regulating the amount of drying medium entering said chamber to vary the relative amounts of drying medium and materials entering said chamber.

6. In flash drying apparatus of the type described in which finely comminuted moisture carrying material is fed into a drying chamber and intimately commingled with and carried by a heated gaseous drying medium at above 212° F. that absorbs moisture from said material and wherein the material and drying medium are withdrawn from the drying chamber and separated and at least a portion of the separated moisture retaining drying medium is mixed with a fresh supply of heated drying medium and returned to the drying chamber for drying wet incoming material; means for regulating the amount of separated drying medium returned to the drying chamber; means for maintaining said material at a substantially constant temperature during the drying period consisting of means responsive to the wet bulb temperature of said drying medium for controlling said regulating means to vary the amount of moisture-carrying drying medium returned to the drying chamber; and means responsive to the dry bulb temperatures of the drying medium at the inlet and outlet of the drying chamber for controlling the amount of drying medium entering said chamber to cause the drying of the material in said chamber to

take place between determined limits of dry bulb temperature while at the constant wet bulb temperature attained by regulation of the amount of moisture carrying medium returned to the drying chamber.

7. In flash drying apparatus of the type described in which finely comminuted moisture carrying material is fed into a drying chamber and intimately commingled with and carried by a heated gaseous drying medium at above 212° F. 10 that absorbs moisture from said material and wherein the material and drying medium are withdrawn from the drying chamber and separated and at least a portion of the separated, moisture-retaining drying medium is mixed with 15 a fresh supply of heated drying medium and cool gas and returned to the drying chamber for drying wet incoming material; means for regulating the amount of separated drying medium returned to the drying chamber; means for regulating the 20 amount of fresh heated gases admitted to the drying chamber; means for regulating the amount of cool gas admitted to the drying chamber; and means responsive to the wet-bulb temperature of the drying medium for controlling 25 said regulating means to proportion the amount of cool gas, the amount of fresh hot gas and the amount of returned drying medium to maintain a substantially constant temperature of said material.

30 ALFRED R. SMITH.
